DESIGN FOR A COMBINED TOOTH POWDER DISPENSER AND TOOTH BRUSH HOLDER

Alfred A. Anthony, New York, N. Y.

Application June 23, 1938, Serial No. 78,002

Term of patent 7 years

To all whom it may concern:

Be it known that I, Alfred A. Anthony, a citizen of the United States, residing at No. 5 West 63rd Street, in the city, county, and State of New York, have invented a new, original, and ornamental Design for a Combined Tooth Powder Dispenser and Tooth Brush Holder, of which the following is a specification, reference being had to the accompanying drawing, forming part thereof.

In the drawing:

Fig. 1 shows a top plan view of a combined dispenser and holder showing my new design;

Fig. 2 is a front elevation of the same; and
Fig. 3 is a view of the same in side elevation.

I claim:

The ornamental design for a combined tooth powder dispenser and tooth brush holder substantially as shown.

ALFRED A. ANTHONY.
